BUTTER PAT DISPENSER

Leila R. Chenkin, 525 E. 86th St.,
New York, N.Y. 10028

Filed Nov. 18, 1968, Ser. No. 14,507

Term of patent 3½ years

Int. Cl. D7—99

U.S. Cl. D52—2

FIG. 1

FIG. 2

FIG. 3

I claim:

The ornamental design for a butter pat dispenser, substantially as shown.
